VAGINAL SPECULUM

Donald M. Olson, Oakland, Calif., assignor to Max Morris, San Jose, and Earl L. Kirkman, Felton, Calif., fractional part interest to each

Filed Aug. 10, 1972, Ser. No. 279,641

Term of patent 14 years

Int. Cl. D24—02

U.S. Cl. D83—12 R

FIG. 1

FIG. 2

FIG. 4

FIG. 3

FIG. 5

FIG. 1 is a perspective view of a vaginal speculum showing my new design;

FIG. 2 is a side elevational view thereof;

FIG. 3 is a top plan view thereof;

FIG. 4 is one end elevational view; and

FIG. 5 is another end elevational view.

I claim:

The ornamental design for a vaginal speculum, substantially as shown.
